LIQUID FILLING MACHINE

Ronald E. J. Nordquist, Maplewood, N. J., assignor
to American Can Company, New York, N. Y., a
corporation of New Jersey

Application January 19, 1934, Serial No. 707,396

12 Claims. (Cl. 226—116)

The present invention relates to liquid filling in containers or cans and has particular reference to machines for vacuum filling cans wherein the exterior walls of the cans are protected against collapse by atmospheric pressure when their interiors are under the relatively high vacuum used as a step in the filling operation and this protection is afforded by a balance of air pressures on the two sides of the can wall.

10 The invention contemplates the vacuumizing of the interior of the container or can at a high vacuum while simultaneously vacuumizing the space surrounding a major part of the can walls to effect a substantial pressure balance during the 15 vacuumizing and filling operations so that the can walls are not subjected to distorting or collapsing influences.

An object of the invention is the provision of a vacuum can filling apparatus for temporarily forming an enclosed airtight chamber surrounding a substantial part of the walls of the can being filled, the interior of the can and the interior of the enclosed chamber both being subjected to vacuum at one step in the filling cycle, the degree of vacuum being further controlled so 25 that a substantial balanced pressure condition is had on both inside and outside of the intervening can walls.

Another object of the invention is the provision 30 of can engaging jaws in a vacuum can filling machine which partially surround a can to be filled when the can is in filling position and which provide an exterior can wall chamber that is airtight. This chamber is then subjected to substantially the same degree of pressure as the 35 interior of the can just prior to and during the filling of the can, so that both the outside and the inside air pressures on the intervening can walls are the same and after filling the jaws are 40 removed from the can and the surrounding chamber then becomes non-existent without interfering with the further operations of the machine.

A further object of the invention is the provision 45 of a no-can-no-vacuum device in such an apparatus for preventing communication between the source of vacuum and the can jaws in the absence of a can to be vacuumized and filled.

Yet another object of the invention is the provision 50 of an automatic valve associated with the chamber forming jaws surrounding the can for admitting atmospheric pressure to the enclosed chamber when the can has been filled and is ready for release.

Numerous other objects and advantages of the 55 invention will be apparent as it is better under-

stood from the following description, which, taken in connection with the accompanying drawings, discloses a preferred embodiment thereof.

Referring to the drawings:

Figure 1 is a fragmentary top plan view of a 5 part of a can filling apparatus embodying the present invention, parts of the apparatus being broken away and parts shown in section;

Fig. 2 is a vertical sectional view taken substantially along the broken line 2—2 in Fig. 1; 10 and

Fig. 3 is a sectional view similar to Fig. 2 showing the same parts in a different position.

It is the present purpose in the drawings and specifications to illustrate and describe only sufficient of an apparatus to give a clear understanding of the features of the present invention and to this end the drawings disclose a portion only of a vacuum can filling apparatus which may be merely a part of a more elaborate machine consisting for example of many filling units, 20 all coordinated for high speed filling action.

Such a disclosure embodies a liquid tank 21 which is closed at its bottom by a plate 22 located in a depression 23 formed in the bottom 24 of 25 the tank. This tank is adapted to contain a filling liquid, indicated by the numeral 25, which is to be filled into a can.

A series of filling head units 31 may be secured to the outer wall of the tank 21, one of these units 30 being illustrated and described in detail. A unit is adapted to receive a can 32 which may be already partially filled with a solid contents 33 such for example as peaches or the like, and which is to be further filled with the liquid 25, which 35 liquid will be syrup in the case of a pack of peaches.

The filling head unit 31 comprises a body 35 (Figs. 2 and 3) which is formed with a reduced neck 36 merging into a vertically extending right angled foot 37 by means of which it is adjustably secured to and carried on the outside wall of the tank 21. Each foot part 37 may be clamped in its adjusted position on the side wall of the tank in any suitable manner. The adjustment 45 of this unit as to height will be again referred to hereinafter and will be more fully described at such time.

Each unit body 35 carries a rubber ring 41 which is held in position inside of a holding 50 ring 42 by an inner clamping ring 43 threadedly secured to a centrally disposed hub 44 formed integrally with the under side of the unit body. The holding ring 42 is formed with a horizontal top 46 which rests against the under surface of 55

the body 35. The inside of the ring is provided with a tapered surface and the rubber ring 41 is pressed against this surface by a correspondingly tapered surface on the outside wall of the 5 clamping ring 43.

A topper block 51 is located on the under side of the hub 44 and is held in fixed position by a dowel pin 52 and a screw 53. This screw is formed with an enlarged head 54 fitting within 10 a depression 55 formed in the topper block and this head cooperates with the topper block serving as an auxiliary topper.

The rubber ring 41 may be formed with an inclined lower wall part 58 which is adapted to be 15 engaged by the upper flange of the can 32 when the latter is raised into position by lifting of a can support unit 59 (Fig. 2). The resiliency of the ring cooperating with the lifting force of the support effects a tight seal between the filling head and the can flange when the can is 20 clamped against the rubber ring in its vacuumizing and filling position. The can support unit 59 is supported and is raised in any suitable manner, this being a usual feature in can filling machines.

It is contemplated that air be removed and a high vacuum be established in the clamped can prior to and during filling. In order to prevent collapse or distortion of the can wall by the relatively excessive atmospheric pressure on the outside of the can at such a time, encircling and protecting instrumentalities are provided.

These instrumentalities comprise fixed and movable jaws. A fixed jaw 61 is carried in the can support unit and is secured to an upwardly extending lug 62. This jaw is slotted at the back (Fig. 1) and the lug 62 fits in the slot and is held in place by a plate 63 and a cap screw 64.

Each plate 63 is extended on its two sides in 40 projecting ribs 65. These ribs engage within and have free sliding vertical movement in grooves 66 formed on opposite sides of spaced depending posts 67 which extend down from a disc 68 located under and movable with the tank 21. 45 A post 67 is positioned between each can support unit and each post therefore serves two adjacent units.

The inner wall of the fixed jaw 61 is hollowed out and corresponds in curvature to the exterior 50 wall of the can body and substantially fits the can when it is in place on the support. The can engaging wall of the jaw extends through substantially 180° and therefore practically half of the can body is surrounded by the jaw.

55 A movable jaw 69 (Figs. 2 and 3) is also provided for encircling the opposite half of the can when it is clamped for filling. This jaw is secured to a U-shaped strap or holding member 70 which is formed with curved arms 71 the ends 60 of which extend on opposite sides of the filling head body 35. The end of each arm is pivotally mounted on a pin 72 carried in a lug 73 (Fig. 1) formed in and projecting up from the body 35. There are two of these lugs on each filling head 65 body, one on each side. The movable jaw is thus hinged on the body and can be moved on the pin 72 through practically 45 degrees.

In the raised position of the movable jaw 69 (Fig. 3) it is substantially above the filling head 70 and when in such position the can 32 may be inserted on the can support unit 59. In its other or lowered position (Fig. 2) the movable jaw is in can protecting position and cooperates with the fixed jaw 61 to completely surround the can 75 for its vacuumization and filling.

A shouldered bolt 74 is carried by the strap 70 and is held in fixed position by a nut 75. A cam roller 76 is rotatably mounted on the bolt. This roller is adapted to engage within a cam groove 77 of a stationary cam 78 which in part 5 surrounds the tank, filling head, etc., of the apparatus. As a filling head unit with its can is carried adjacent the cam its roller enters the cam groove 77. This cam track determines the hinging action of each movable jaw and its support. In this manner the jaw 69 is lifted (Fig. 3) and lowered (Fig. 2).

With the jaw 69 in lowered position and engaging the can, the filling head unit passes adjacent the end of the cam 78 and the cam roller 76 15 leaves the cam groove 77. The passing filling head unit now moves adjacent a second and this time a horizontal cam 81. The ends of the cams 78, 81 overlap each other as illustrated in Fig. 1. The cam 81 now becomes effective in the following manner.

A cam roller 82 is mounted on a pin 83 secured in lugs 84 of a bracket 85 which is pivoted on shaft 86 held in lugs 87 projecting outwardly from the rear of the jaw 69. A spring barrel 91 25 slidably located within a bore 92 of the bracket 85 is interposed between the bracket 85 and the jaw 69 and a spring 93 confined within the barrel exerts a pressure between these members 85, 69. This keeps the roller 82 in engagement with the cam 30 bracket 81 and holds the jaw 69 in close engagement with the body wall of the can.

The walls of the jaws 61, 69 do not directly engage the can wall but these walls are held away from the can wall a relatively small distance. 25 The intervening space between the inside walls of the jaws and the outside walls of the can thus provided is utilized as an airtight chamber.

The movable jaw 69 is provided with grooves 95 40 cut into its inner surface parallel to and adjacent its top and bottom edges. Rubber strips or circular half rings 96 are located in these grooves and project outwardly from the inner face of the jaw. When the jaw is holding a can the inner faces of these rings directly engage the can wall and 45 extend through one half of its circumference. This forms a space 97 (Fig. 2) between the walls of the jaw and the walls of the can which extends vertically between the rubbers, this being nearly the full height of the jaw and a distance corresponding to a large part of the can height.

The fixed jaw 61 is similarly provided with grooves 101 (Fig. 3) cut into its inner face parallel to and adjacent its top and bottom edges. Other rubber strips or semi-circular members 102 55 are located in the grooves and these project from the face of the jaw in the same manner. The inner faces of the rings directly engage the opposite sides of the can so that it is entirely surrounded adjacent its top end and adjacent its bottom end by abutting semi-circular rubber members together constituting a complete ring 96—102.

A space 103 between the wall of the jaw 61 and the wall of the can is thus provided which extends 65 vertically between the rubber rings 102. When the jaws are fully closed on the cans and the ends of the rubbers 96, 102 abut, the two spaces 97, 103 communicate and together constitute an annular chamber extending entirely around the 70 can wall.

To completely seal this chamber and make it airtight the vertical front edges of the jaw 61 on both sides are provided with grooves 105 (Figs. 1 and 3). A rubber strip 106 may be inserted in 75

each vertical groove and the outer faces of these strips engage the front edges of the jaw 69 insuring a complete closure between the jaws at this position. Each groove 101 at its end terminates in the vertical grooves 105 and the rubber rings 102 which fill the grooves 101 may be formed integrally with the strips 106 of the grooves 105 as best shown in Fig. 3.

To insure an easy centering of the two jaws one with the other when closing on a can the edges of the jaw 61 are also formed with vertical projections 108 having inner inclined faces 109. These faces slope toward the rubbers 106 and guide the edges of the moving jaw 69 as it closes in toward the fixed jaw 61.

The body 35 of the filling head unit 31 is cut through in a port 115 (Figs. 2 and 3) which passes vertically through it and through the topper 51. This port provides a connection between the interior of a clamped can 32 when it is positioned in the unit and a channel 116 formed in a valve unit 117, the latter being located on the body 35. This valve unit 117 has movement upon the upper surface of the body and shifts the position of its channel 116, the engaged surfaces of the two members being substantially airtight in all positions of the valve.

The valve 117 is mounted on the lower end of a hollow shaft 118 journaled in a bearing 119 formed in a bracket 121. This bracket is held in its seat 122 formed in the side of the tank 21 by clamps 123 which are held in position by nuts 124 threadedly engaged on the outer ends of studs 125 secured in the side wall of the tank.

The vertical adjustment of the filling head units 31 which has been previously mentioned is effected in a convenient manner and for this purpose there is provided a bolt 128 which is threadedly engaged within the inner portion or foot of the bracket 121. This bolt is formed at its lower end with a head 129 which can turn in a T slot 131 cut in the foot 31 of the filling head unit. A nut 132 is preferably pinned to the upper end of the bolt 128 to provide a convenient means for turning it to effect such adjustment.

At the vacuumizing stage of the filling operation when the valve channel 116 is moved into vacuumizing position in registry with the port 115, the air is withdrawn from the interior of the can in the following manner.

The valve channel 116 communicates with an elongated port 135 formed in the body 35. This port 135 at its opposite end communicates with an inclined passage 136 formed in the bottom 24 of the tank 21, the inner lower end of which leads into a vacuum chamber 137 located below the liquid chamber of the tank. This chamber 137 is suitably connected at all times with a source of vacuum and any air entering the chamber is immediately withdrawn. At the time of vacuumizing, therefore, air from the clamped can 32 is withdrawn along the path of communication comprising the port 115, channel 116, elongated port 135, passage 136 and the vacuum chamber 137.

The chamber combining the spaces 97, 103 which surrounds the can wall is also vacuumized at the same time that the interior of the can is under vacuum and this balances the pressure conditions on both the can interior and exterior. To obtain such simultaneous action the jaw 61 is cut through with a horizontal port 141 (Fig. 2), one end opening into the space 103 and thence into the chamber surrounding the can wall, the other end communicating with a vertically dis-

posed chamber or well 142 located in the side wall of the jaw and extending down from its top edge a substantial distance throughout the depth of the jaw. This well 142 is closed at the top by a screw plug 143. The bottom of the well 142 is perforated and an aperture 144 communicates with a short horizontal port 145. When the can support unit 59 is in its raised position (Fig. 2) the horizontal port 145 is aligned and in communication with a bore 147 formed as a lateral extension and located at the bottom of a vertically disposed passage 148, both bore and passage being disposed in the post 61. The top of the passage 148 is closed by a screw plug 149.

The passage 148 at its top communicates with a horizontal port 159 extending substantially radially of the disc 68 and the inner end adjacent a central open part 161 of the disc is closed by a screw plug 162. Near the inner end of the port 159 a lateral, vertically extending opening or outlet 163 is cut through the disc wall and is in registry at all times with a vertical port 164 formed in the lower portion 24 of the tank 21. The upper end of the port 164 leads into the vacuum chamber 137.

It is this chamber common to both the interior and exterior of the clamped and positioned can that insures at all times the same pressure on the two sides of the can wall when both the can interior and the confined spaces 97, 103 on the can exterior are in open or unrestricted communication with the vacuum chamber.

This open or unrestricted condition is not present if there is no can in place on the can support unit 59 as there is then neither can interior nor can exterior as considered in the present connection. The movement of the valve 117 prevents opening of the air line through the filling head unit 31, but this forms no part of the present invention and is therefore omitted. There is also provided a shut-off valve 171 (Figs. 2 and 3) in the bottom of the well 142 for controlling the communicating passages leading to the can exterior and this will now be described.

The valve 171 is formed on a stem 172 passing through the aperture and port 144, 145 and is mounted for sliding movement in a bore 173 formed in the lower part of the jaw 61. The lower end of the stem 172 projects below the jaw 61 and carries a collar 175 which is engaged by a spring 176 housed in a recess 177 formed in the bottom of the jaw. This spring tends to keep the valve 171 down against its seat in the bottom of the well 142 closing the aperture 144 and thereby cutting off communication with the vacuum chamber 137.

Valve 171 is only opened when there is a can on the can support unit 59. A floating bar 181 is used to open the valve and is located within a slot 182 formed in the top of the can support unit. This bar is slotted at 183 and a pin 184 passes through the slot, its ends being secured in the body of the unit. Bar 181 may slide longitudinally and may also rock on the pin 184 while confined within the slot 182.

The bar 181 is normally urged outwardly by a spring 186 disposed within a slot 187 formed in the can support unit 59. One end of this spring is secured to the bar and its other end engages over a pin 188 held within the slot 187. This spring when unrestricted also pulls the bar 181 down against a bridge member 189 interposed between the front of the slot 182 and the slot 187. The pin 184 limits the forward movement of the bar.

The rear end of the bar 181 adjacent the jaw 61 is formed with an offset portion 191 which protrudes above the top of a can support unit 59 and in the path of travel of an incoming can 32, 5 the bar being then pulled forward and its front end in lowered position as just described.

A can coming into place upon the top of the can supporting unit 59 moves over the bar 181 without touching it, this bar at such time being 10 forward and in horizontal position within its slot. The bottom seam or rim of the can comes against but does not move the foot 191 of the bar. It will be observed (Fig. 1) that the bar and slot are off center and to one side of the can 15 support unit 59. When the can is placed on the can support it is well within the jaw 61 but is not fully seated.

The can is next raised by the support unit, the 20 entire tank and filling head structure being continuously carried around on the axis located at the center of the tank. As the can is raised the movable jaw 69 (Figs. 2 and 3) under the influence of the cam track 77 begins to descend towards and around the exposed part of the can 25 body and the flange at the open top of the can strikes against the rubber 41 and flange and rubber are then pressed into tight engagement as the can support reaches the end of its upward movement.

30 At the same time the rising jaw 61 sliding along depending adjacent posts 67 and the block ribs 65 moving in the guideways 66 bring the port 145 into alignment with the bore 147 and communication is established with the vacuum chamber 137. 35 The valve 171 is still closed so that only the port is evacuated at this time.

When the movable jaw 69 is nearly closed on the can it passes under the influence of the cam 81 which forces it horizontally and inwardly, 40 squeezing the two jaws tightly together and bringing the can into its fully seated and central position. This last shifting movement of the can through the engagement of its lower can seam and the offset portion 191 of the bar 181 slides 45 the latter back and moves it just enough to open the valve 171 in the following manner.

The offset portion 191 (Fig. 2) on the rear of the bar 181 is in engagement with a depending leg 192 of a bell crank lever 193 as long as the bar 50 is in a horizontal position within its slot 182. This bell crank lever is pivotally mounted on a stud 194 secured in a lug 195 which projects down from the jaw 61. A second leg 196 of the bell crank lever extends back and under the lower 55 end of the valve stem 172. When the jaws are fully closed on the can the last slight movement of the can and the bar 181 rocks the bell crank lever and opens the valve 171.

Opening of the valve 171 immediately opens 60 the communication between the chamber formed by the confined spaces 97, 103 and the vacuum chamber 137 and the former is vacuumized. Co-incident with this action the valve 171 establishes communication between the vacuum chamber 137 and the inside of the can. In this manner both the interior and exterior parts of a clamped can are vacuumized and a balanced pressure condition is maintained on both sides 65 of the can walls, preventing collapse or distortion of the can while filling which follows in the regular manner.

When a can has been filled with the liquid from the tank 21 and its valve 171 has been restored 70 to its former closed position, it is ready to be re-

leased from the rubber 41. At such time the interior of the filled can is open to atmosphere.

The can has now reached a place in its circular path of travel with the revolving tank and the filling head unit where it moves adjacent a stationary cam 201 (Figs. 1 and 3) mounted on a stationary frame part of the machine. The front end of the bar 181 engages this cam and rides up an inclined face of the cam. This action pivots the bar on its pin 184, lifts its front end, depresses its rear end, and withdraws the offset portion 191 from engagement with the seam of the can. The bell crank lever 193 under the action of the spring 176 immediately rocks on its pivot, and the valve 171 snaps into closed position, cutting off communication between the vacuum chamber 137 and the exterior wall of the can.

Just before the roller 82 leaves the cam 81 the cam surface recedes and the pressure exerted on the movable jaw 69 is relieved so that the bracket 85 moves back a slight distance away from the jaw under the influence of the spring 93. This action uncovers an air port 205 formed in the wall of the jaw which is held closed during the vacuumizing and filling just described by a small pad carried on a spring barrel 206 which constitutes a vent valve for the can wall spaces 97, 103. This barrel is slidably held within a bore 207 formed in the upper part of the bracket 85. The spring barrel is provided with an enlarged head 208 which is backed up by a spring 209 disposed within a bore 211 formed adjacent to the bore 207.

When the aperture 205 is uncovered atmospheric air is admitted to the chamber surrounding the can wall, thus breaking the vacuum. The movable jaw 69 is now lifted as the roller 76 engages the cam groove 77 and this is immediately followed by a lowering of the can support unit 59 which brings the filled can back into position and ready for discharge. Since the top of the can is open to atmosphere there is no resistance to separation of the can flange from the filling head rubber wall 58.

If, in the next cycle there is no can placed on the can support unit 59 there will be no engagement of the bar 181 with the pivoted lever 193 and the valve 171 will remain closed throughout the cycle. This feature constitutes the no-can-no-vacuum operation of the present invention.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof:

I claim:

1. In a vacuum filling machine for cans, the 60 combination of a rotary filling head unit for filling liquid into cans while in said unit, cooperating instrumentalities each adapted to partially surround and engage the side walls of a said can to form an annular space between said instrumentalities and the can wall, and means for vacuumizing the interior of said can and the said annular space between said instrumentalities and the can wall to prevent can wall distortion.

2. In a vacuum filling machine for cans, the 70 combination of a rotary filling head unit for filling liquid into cans while in said unit, cooperating instrumentalities each adapted to partially surround and engage the side walls of a said can to provide a closed annular chamber on the out- 75

side of the can, and means for vacuumizing the interior of said can and the said annular chamber to prevent can wall distortion.

3. In a vacuum filling machine for cans, the combination of a rotary filling head unit for filling liquid into cans while in said unit, means engageable with the side wall of a can for forming an annular chamber around a substantial part of the outside of the can wall, and means for simultaneously vacuumizing both the can interior and said annular surrounding chamber to maintain a pressure balance on both inside and outside of the can wall.

4. In a can vacuum filling machine, the combination of a rotary filling head unit for holding a can to be vacuumized and filled, and means for equalizing the air pressures on the interior and exterior of the can during such vacuumizing and filling to prevent distortion of the can walls, said equalizing means including complementary members having sealing engagement with side walls of a held can to provide a closed vacuum chamber partially defined by the said can side walls.

5. In a vacuum filling machine for cans, the combination of cooperating movable and fixed parts adapted to hold a can to be filled, said movable part being mounted for pivotal movement towards and away from the side wall of the can, means for swinging said pivotally movable part towards and away from the side wall of the can, means for closing off the open end of said can, said movable and fixed parts together with said can defining a closed chamber, and means for vacuumizing said chamber.

6. In a vacuum filling machine for cans, the combination of relatively movable and fixed parts adapted to surround an open end can and to define a chamber, said movable part being mounted for pivotal movement towards and away from the side wall of the can, means for swinging said pivotally movable part towards and away from the side wall of the can, means for closing off the open end of said can, and means including the said can surrounding chamber for balancing the pressure exteriorly and interiorly of said can.

7. In a vacuum filling machine for cans, the combination of relatively movable jaws adapted to surround an open end can and to define a chamber, means for closing off the open end of said can, means for vacuumizing said chamber and the interior of said container, and valve

means for cutting off said vacuum connection from the interior of said container prior to filling the same.

8. In a vacuum filling machine for cans, the combination of relatively movable jaws adapted to contain an open end can and to define a chamber on the outside of said can, means for closing off the open end of said can, means for vacuumizing said chamber, and valve means for cutting off the vacuum connection from said chamber.

9. In a vacuum filling machine for cans, the combination of cooperating clamping jaws adapted to engage the exterior of a can and to define a chamber, means for vacuumizing said chamber, valve means for controlling the said vacuumization of said chamber and means affected by the presence of a said can in said jaws for actuating said valve means.

10. In a vacuum filling machine for cans, the combination of a pair of clamping jaws adapted to hold a can to be vacuumized and filled and to define a chamber on the outside of said can, means for vacuumizing said can surrounding chamber, and means associated with the said jaws for venting said chamber following the vacuumizing and filling of said can.

11. In a vacuum filling machine for cans, the combination of a pair of clamping jaws for temporarily defining a chamber around the outside wall of an open top can, means for closing off the open top of said can, and means for connecting said surrounding chamber and the interior of said can with a common source of vacuum for simultaneously vacuumizing both the interior of said can and the interior of said chamber to balance the pressures existing interiorly and exteriorly of said can to prevent its collapse and distortion.

12. In a vacuum filling machine for cans, the combination of cooperating clamping jaws adapted to engage the exterior of a can and to define a chamber, means for vacuumizing said chamber, valve means for controlling the said vacuumization of said chamber, devices operable by a said can in said jaws for opening said valve means to effect the said vacuumization of said chamber, and an actuating member for tripping said device to close said valve means prior to the removal of said can from said jaws.

RONALD E. J. NORDQUIST.
